UNITED STATES PATENT OFFICE.

JOSEPH F. RADERS, OF NEW YORK, N. Y., ASSIGNOR, BY MESNE ASSIGNMENTS, TO THE AUTOMATIC PHOTOGRAPHIC MACHINE COMPANY, OF WEST VIRGINIA.

AUTOMATIC PHOTOGRAPHING-MACHINE.

SPECIFICATION forming part of Letters Patent No. 581,998, dated May 4, 1897.

Application filed January 5, 1895. Serial No. 533,926. (No model.)

To all whom it may concern:

Be it known that I, JOSEPH F. RADERS, of the city, county, and State of New York, have invented a certain new and useful Improvement 5 in Automatic Photographing-Machines, of which the following is a specification.

My invention has for its object the production of an automatic photographing-machine in which the action of the various operative 10 mechanisms are in part controlled by a suitable fluid under pressure as distinguished from rigid connections.

The invention further provides, in combination with the foregoing, a motor of any suitable construction which is adapted to so control and regulate the flow of the fluid under pressure to the various operative parts that the latter shall perform their several functions in their proper sequence. Means are 20 also provided by which the operative parts of the machine are set in motion by the insertion of a coin of proper value.

I will describe an automatic photographing-machine embodying my improvement, and 25 then point out the novel features in the claims.

In the accompanying drawings, Figure 1 is a sectional elevation taken on a plane parallel to the side of the machine. Portions, however, are in this figure shown in full side 30 view. Fig. 2 is a rear view of the machine, the rear wall of the inclosing case being removed and some parts being shown in section. Fig. 3 is a plan view of a plate-holder comprising a pair of jaws and means for operating 35 the same comprised in the improvement.

Fig. 4 is a plan view showing an approved method of imparting to the plate magazine or box a step-by-step forward movement. Fig. 5 is an outline view of a series of cams and 40 their coacting parts. Fig. 6 is a longitudinal section showing the construction of an engine which may be utilized for actuating any of the mechanisms comprised in the machine.

Similar letters of reference designate corresponding parts in all the figures.

As my invention is directed toward the production of various mechanisms and devices which are necessary for the purpose of carrying a sensitized plate through the various operations and movements incident to the pro-

duction of a completed photograph and its delivery to the outer portion of the machine and the adaptation of these parts as well to enable them to be operated in part by a suitable fluid under pressure I have shown such 55 parts as are essential to my invention in detail. Other parts to which my invention does not relate are not so shown or are omitted altogether.

A is the inclosing box or chamber, within 60 which the mechanisms and devices constituting the improvement are contained. It may be of any suitable shape or material and is provided in one of its walls with an inwardly-convergent tube or light shaft B. A lens-tube B' may be secured to the inner or smaller 65 end of the light-shaft B and carries a suitable lens or arrangement of lenses B². The light-shaft B is preferably convergent inward or cone-shaped, as this form will assist in the 70 concentration of the light upon the lens B² and permit of a considerable variation in the height of the subject posing in front of its outer orifice.

A plate-holder C is arranged at the rear of 75 the lens B² at such a distance therefrom that the image of the subject situated at a convenient distance in front of the orifice of the light-shaft B will be properly formed upon the sensitized plate contained within the 80 plate-holder. A divergent tube C' may be secured at the rear of lens-tube B' and extended rearward to the vicinity of the plate-holder C.

D is a shallow box placed immediately at 85 the rear of the lens-tube B'. It may be secured to the lens-tube, while the divergent tube C' may be attached to its opposite face. The box D is provided with an opening D' in the extension of the focal-axis of the lens B², 90 the opening being controlled by a suitable shutter D², here shown as being sector-like in form and pivoted at its end portion within in the box D by a pin d. The shutter D² is provided with an arm d', extending on the 95 side of the pin d opposite to that on which the main body of the shutter is situated and suitably connected with the piston-rod d² of an engine d³, supported on one of the walls of the box D.

In the present instance for controlling the movements of the operative mechanisms I have shown engines which are provided with reciprocating pistons whose piston-rods are 5 in direct engagement with the moving part or parts of the various mechanisms. These cylinders may be of the general construction represented in Fig. 6, in which E is a cylinder, E' the reciprocating piston, e the piston-rod, attached to the piston and passing outward through a suitable stuffing-box e' at the end of the cylinder. A spring e² may be utilized to return the piston to one end of its stroke. It is designed that the piston shall 15 be moved in the direction opposite to that in which it is forced by the spring by a suitable fluid under pressure admitted to the cylinder, which after performing its function in moving the piston to the end of its stroke 20 will be exhausted through a suitable duct or passage.

I do not wish to be limited to the use of a spring as a retractive device, however, as other means or equivalents may be employed. 25 For instance, a weight may be attached to the moving part by a cord running over suitable pulleys, or the spring may be placed outside the cylinder.

Any suitable fluid under pressure may be 30 utilized for moving the pistons—for instance, air or water, but I prefer air, making the machine thereby throughout pneumatically operated.

A convenient framework or standard F is 35 supplied for carrying and supporting the various parts of the machine.

G is a plate magazine or box carrying the supply of sensitized plates. It may consist of an oblong box whose interior transverse 40 dimensions correspond with the dimensions of the plates. The plates may be fitted in grooves g⁰, provided in the sides of the box to maintain them in an upright position.

G' G' are guideways or tracks on which the 45 magazine G may slide to and fro.

G² is a chute secured below the magazine G, but independent therefrom and serving to direct the downwardly-moving plate from the magazine G to its proper position relatively to the lens B², where it is held by the plate-holder C, presently to be described.

For the delivery of the plates from the magazine G one after another I contemplate in the present instance giving to the magazine a 55 step-by-step movement, the distance the magazine is carried at each step corresponding to the distance between the plates in the magazine. The magazine G is provided with an independent bottom plate g, which is prevented 60 from moving with the magazine G by a stop g', and consequently as the magazine is moved forward the plates will be delivered to the chute G² in succession, descending through the latter to the plate-holder C.

65 I have shown a convenient way of imparting to the magazine G a step-by-step movement. Its outer surface is provided with a

series of ratchet-teeth g³, (see Fig. 4 more especially,) with which engages a finger g⁵, fitted into a suitable opening in a pivoted lever g⁴ and thrust into engagement with the teeth g³ by a spring g⁶. The piston-rod g⁶ of a cylinder g⁷ is adapted to swing the lever g⁴ about its pivot or fulcrum point g⁸. It is evident that a reciprocation of the piston-rod g⁶ will impart to the magazine G an intermittent or step-by-step forward motion.

II II are retaining-jaws forming the plate-holder C and serving to grasp the plate as it descends through the chute G² and hold the same at the rear of the lens B². The jaws are pivoted by pins h h to a supporting-plate h', which is itself carried by a suitable appurtenance of the supporting-framework F. The inner ends of the pivoted jaws II II may be 85 provided with pins h² h³ to engage with a notched plate h³, carried at the extremity of the piston-rod h⁴ of cylinder h⁵. An outward movement of the piston of the cylinder h⁵ will effect a disengagement of and an inward 90 movement of the same will effect an engagement with a plate interposed between the jaws II II.

I is a carrier, whose purpose is to depress and to withdraw the exposed plate into and 95 out of the several solutions necessary for its development, fixing and washing, and finally to deliver the plate to a delivery-chute. It will be seen to comprise a slotted frame I', through which the plate may move, and a holding-dog I², which is pivoted to the side of the frame and may be swung into and out of the slot to pinch the edges of the plate against the frame holding the plate or disengaging it 100 from the plate entirely.

I³ is a cylinder carried by the frame I', whose piston-rod i engages with an arm of the pivoted holding-dog I² to swing the dog into and out of the slot of the frame I'. A spring i' may be used to insure the withdrawal of the 105 dog I² from the slot.

I⁴ I⁴ are upright cylinders attached to a stationary bracket and having piston-rods i² i³, which engage with and give the carrier I a vertically-reciprocating motion.

The movements of the jaws II II, the frame I' and the holding-dog I² are so timed that the dog will have forced the edges of the plate against the sides of the slot of frame I' before the jaws II II have relinquished their hold 120 upon the sides of the plate.

K is the movable bath or vessel for holding the various fluids to develop, fix, and wash the exposed plate. It is shown in the form of a box comprising four compartments K' K² K³ 125 K⁴. The developing and fixing solutions may be placed directly in compartments K' and K², respectively, but I prefer to use separate cells for containing the solutions and insert the cells in the compartments.

The movable bath K is provided with suitable rollers k k k k, which travel upon a suitable track which may consist of the upturned leg of angle-irons k' k'. The piston-rod K⁵

of cylinder K⁶ serves as a convenient means for causing the reciprocation of the bath K. The compartment K³ contains the washing-water, while the last compartment K⁴ receives the washed and finished plate, from whence it passes to the delivery-chute L. The compartment K⁴ is provided with a slide L', forming the bottom of the compartment, which may be moved to one side, permitting the developed and washed plate to fall through. This displacement of the slide L' takes place when the compartment K⁴ is directly above the mouth of chute L. The slide L' is provided with a tongue L², which enters a recess in a block L³, secured to the under surface of the bath K. A spring l continually presses the tongue L² outward, tending to close the opening through the bottom of the compartment K⁴. A stop l' is interposed in the path 20 of a shoulder l³, provided on the slide L'.

The impetus of the bath K as it moves forward with the finished plate in compartment K⁴ under the influence of the spring of cylinder K⁶ or other retractive device is sufficient as the stop l' and shoulder l³ engage to compress the spring l, carrying the slide L', from under the compartment K⁴, when the plate passes downward to the delivery-chute L and thence outward.

I have shown a series of valves M M' M² M³ M⁴ M⁵ M⁶ M⁷ for controlling the flow of the motive fluid to and from the several cylinders for actuating the various mechanisms comprised in the machine. In the present instance I have shown a separate valve for each cylinder. Each valve may be carried on a bracket m, supported in any suitable manner. Each valve comprises a chambered block m', within which is fitted a rotary plug m², provided with a stem m³. A cover-plate m⁴ may be provided to inclose the plug m² within the block m'. Each valve-block m' is provided with three ports m⁵ m⁶ m⁷, one, (see Fig. 2,) in the present instance m⁷, being at the top, while the remaining two, m⁵ m⁶, are at opposite sides of the block. The port m⁵ at the inner side of the valve-block m' of each of valves except valve M³ is continued through a suitable conduit m⁸ to a supply-chamber M⁹, containing the motive fluid under pressure. The port m⁶ at the opposite side forms the exhaust, while the port m⁷ at the upper portion of the block is continued upward through a suitable conduit to the corresponding cylinder.

As illustrated, port m⁷ of valve M is continued through a conduit m⁹ to the cylinder d³, whose piston actuates the shutter D². Port m⁷ of valve M' is continued through a conduit m¹⁰, which branches at its upper end and enters cylinders I⁴ I⁴, whose pistons actuate the carrier I. Port m⁷ of valve M² is continued through a conduit m¹¹ to the cylinder I³, whose piston actuates the dog I². Part of this conduit will consist of flexible tubing to permit of the vertically-reciprocating movement of the cylinder I³ as it moves to and fro with the

carrier I. Port m⁷ of valve M³ is continued through a conduit m¹² to the water-compartment K³ of the bath K. A portion of this conduit will also preferably consist of a flexible tubing to permit of the reciprocation of the bath. Port m⁷ of valve M⁴ is continued through a conduit m¹³ to the cylinder g⁷, whose piston actuates the plate-magazine G. Port m⁷ of valve M⁵ is continued through a conduit m¹⁴ to the cylinder K⁶, whose piston actuates the bath K. Port m⁷ of valve M⁶ is continued through a conduit m¹⁵ to the cylinder h⁵, whose piston actuates the jaws H II. Port m⁷ of valve M⁷ is continued through a conduit m¹⁶ to a cylinder N, whose piston may be utilized to actuate a slide N' to control the slot or opening for the insertion of a coin. This slide may consist of a swinging arm, to which the piston-rod N² of the piston with which the cylinder N is supplied engages to shift the slide across the slot-opening to prevent the insertion of a second coin while the machine is in process of finishing an exposed plate. After the plate has been delivered the slide N' will be swung to one side away from the slot-opening.

The rotary plug m² comprised in each valve is provided with an angular passage m¹⁷ extending through it, which at one end of the movement of the plug will throw the ports m⁶ and m⁷ into communication and at the other end of its movement will throw the ports m⁵ and m³ into communication. Hence when the plug m² of either of the valves M M' M² M³ M⁴ M⁵ M⁶ M⁷ is moved to one end of the movement pressure will be admitted to the corresponding cylinder, while at the opposite end of its movement the motive fluid will be exhausted from the cylinders, the piston of which will be returned to its normal position under the influence of the spring or other retractive device.

For the purpose of operating the plugs m² of the various valves I have supplied the stem m³ of each plug with a lever-arm O, whose free end is pivoted to one arm of an elbow-lever O'. There are as many of these elbow-levers O' and lever-arms O as there are stems m³; but for the sake of clearness in Fig. 1 I have shown but one, but it will be understood that there is one for operating each plug m². These elbow-levers O' are fulcrumed to a shaft O², carried in suitable brackets O³ O³, supported by the machine. The outer end of the free arms of each elbow-lever O' is brought into engagement with the periphery of a suitable peripheral cam by a spring O¹. I have shown eight of these cams, one for actuating each elbow-lever O' and consequently each plug m². Cam P operates the plug m² of valve M, cam P' that of valve M', cam P² that of valve M², cam P³ that of valve M³, cam P⁴ that of valve M⁴, cam P⁵ that of valve M⁵, cam P⁶ that of valve M⁶, and cam P⁷ that of valve M⁷.

P⁸ is the cam-shaft to which the several cams are affixed. It rotates in suitable bear-

ings P^9 P^9 and is given an intermittent forward motion through the medium of a star-wheel P^{10} , attached at its extremity.

As the proper operation of the mechanisms comprised in the present invention will necessitate five distinct periods of rest, including that in which the parts have assumed their normal positions, comprising the exposure, the retention in the developing solution, the retention in the fixing solution, the washing and the return to the normal position assumed after the final deposition in the receiving-compartment of the bath K, and the movement of the bath forward depositing the finished plate into the delivery-chute L, I have divided the complete rotation of the cam-shaft P^8 into five separate steps, separated by periods of rest. Consequently the star-wheel P^{10} will comprise five fingers or arms.

R is a disk provided with a series of pins r , in the present instance comprising five, projecting from the inner radial face, the pins being adapted to contact with and imprint to the star-wheel P^{10} an intermittent motion as the disk is rotated. These pins may be made adjustable, if desired, whereby ready means are offered for regulating the length of the periods of rest of the cam-shaft P^8 .

I have shown a suitable motor for rotating the disk R . It is seen to comprise a drum R' , within which may be coiled a spring (not shown) in the usual manner, a regulator R^2 , a train of intermediate gearing R^3 , and a pair of bevel-wheels R^4 R^5 , for transmitting motion to the shaft r' of the disk R . I have shown this form merely for illustration, but I do not wish to be confined to its use, as other forms and arrangements of driving mechanisms or motors may be advantageously utilized without departing from the spirit of my invention.

S is a detent fitting into a notch or into notches of one or more of the moving parts of the motor, and when so engaged locking the same from movement. It may consist of a pivoted bar with one or more teeth. At its free end it extends immediately above one arm of a double-armed lever S' , pivoted to a standard S^2 . The opposite arm of the double-armed lever S' is provided with a pocket s , which is placed immediately below the lower end of the coin-chute S^3 . Normally the lever S' is in a horizontal position, but when a coin is received through the chute S^3 and drops into the pocket s the lever S' becomes overbalanced, the end carrying the coin descends, the opposite end ascends, raises the detent-lever S , disengages the motor, which thereupon rotates the disk R and actuates the cam-shaft P^8 . When the teeth of the detent-lever S are again in alinement with the notches provided for them, they reenter the same, locking the motor from further movement. The coin has in the meantime descended until the floor of the pocket s has assumed a horizontal or slightly-inclined position, when the

coin rolls out through the open end of the pocket s and drops into the casing A. The lever S' then assumes its normal position.

T is a vibrating lever forming a latch fulcrumed at t to a pin carried by a bracket t' , attached to the framework F. Its upper end is adapted to enter and withdraw from notches t^2 , provided in a plate t^3 , secured to the under side of the bath K. Its lower end contacts with pins or studs t^4 t^4 , provided on the cam P^5 , which operates to throw the upper end of the lever T out of engagement with the slots of plate t^3 , while a spring t^5 is applied to withdraw it into engagement with the slots.

I have shown in Fig. 5 the several cams removed from their shaft and have also divided the angle subtended by the arc traced by any point on the cam during a complete revolution of the latter—namely, three hundred and sixty degrees—into five equal parts, representing the five successive movements during the intermittent movement of the cam-shaft. Thus 1 2 represent the movement during the first fifth of the full rotation; 2 3, that during the second fifth; 3 4, that during the third fifth; 4 5, that during the fourth fifth, and 5 1 that during the last fifth. I have also shown the free end of each elbow-lever O' in the position which it assumes in the machine relatively to its respective cam.

With the assistance of the figure the operation and sequence of movement may be described as follows: Assuming that a coin has been deposited in the coin-slot, has descended the chute S^3 , and passed into the pocket s , thus disengaging the motor in the manner already described, the disk R revolved, and the first pin r of the same contacts with one of the fingers of the star-wheel P^{10} . Before any movement has taken place the cams and ends of elbow-levers O' are in the relative positions shown in Fig. 5. During the first fifth of the complete rotation of the cam-shaft P^8 —namely, from 1 to 2—which terminates after the first pin has passed out of contact with the first finger of the star-wheel, cam P operates to rotate the plug m^2 of valve M to open communication between the ports m^5 and m^7 of said valve. This movement takes place owing to the fact that cam P is reduced in diameter for a portion of its circumference, the free end of the elbow-lever dropping into the recess produced by this reduced portion and shifting the plug of the valve in a manner evident from the foregoing description. By this movement the motive fluid is admitted to cylinder d^3 , and the shutter D^2 is opened and held open for a space of time almost equal to a fifth of the revolution of the cam. Just before the cam reaches the end of its first movement the elbow-lever O' is shifted back to its original position, thereby throwing ports m^6 and m^7 in communication, when the motive fluid is exhausted from cylinder d^3 , and the shutter D^2 is moved back to its normal position, closing the opening for the exposure of the plate. It is evi-

- dent that during this portion of the movement no function is performed by cams P' , P^2 , P^5 , and P^6 . Cam P^4 , however, is provided with a notch in its periphery between points 1 2. 5 Consequently during this movement plug m^2 of valve M^4 will be operated to admit the motive fluid to and exhaust it from cylinder g^7 . This will operate in the manner already explained to carry the plate-magazine forward 10 and deliver a plate to the carrier C. On comparison of cams P and P^4 , as represented in Fig. 5, it is evident that cam P^4 will operate before cam P. Hence before the shutter D² is moved to one side a plate will have descended into the holder C. Immediately after the operating-motor of the machine has been set in motion by the insertion of a coin 15 cam P^7 will operate to admit the motor fluid to cylinder N, shifting the slide N' across the 20 coin-slot and closing the same. It will preferably remain closed during the entire operation of the machine. The several cams will now remain in the same position where the free ends of the elbow-levers O² are at the 25 point 2 until the second pin of disk R will have contacted with the second finger of star-wheel P^{10} . During the movement 2 3 cams P P^3 P^4 P^5 are inoperative. Cam P^2 will be the first to operate during this movement. 30 It will operate the plug m^2 of valve M^2 to admit the motive fluid to cylinder I³, thrusting in dog I² to grasp the plate in carrier I by its upper edges. It will be thus held during the succeeding manipulations of the plate. Cam 35 P^6 will be the next to operate, shifting the plug m^2 of valve M^6 to admit the motive fluid to cylinder h⁵, releasing the grip of the jaws H H upon the plate. Lastly, just before the cam-shaft comes to rest, due to the passing 40 of the second pin on disk R out of engagement with the second finger of star-wheel P^{10} , cam P' will operate to shift the plug m^2 of valve M' , admitting the motive fluid to cylinders I⁴ I⁴, which move the carrier I downward and thrusts the plate into the developing 45 solution carried in compartment K'. The various cams have now reached position 3, and the plate is held suspended in the developing solution until the third pin of disk R has contacted with the third finger of the 50 star-wheel P^{10} . Immediately upon the commencement of the movement 3 4 pressure is released from the cylinders I⁴ I⁴ and the carrier I is drawn upward by the spring within 55 the cylinder or other retractive device, and the operation of cam P^5 soon follows to shift the plug m^2 of valve M^5 to admit the motive fluid to cylinder K⁶ to move the bath K backward from the position shown in Fig. 1, so 60 that the fixing solution carried in compartment K² shall be immediately below the plate-carrier I. To permit of this backward movement of the bath, it must be unlocked from latch T. To this end the pins t^4 t^4 , extending 65 from cam P^6 , are so arranged that one of them has oscillated the latch on its pivot-pin to throw it out from engagement with a slot t^2

in the plate t^3 , affixed to the bath K, but has left it free to be withdrawn into the next slot by the spring t^1 . Pressure may be kept upon the piston of cylinder K⁶ during the remainder of the operation of the machine and its movement controlled by the latch T. The cams have now completed the third fifth of their movement and the carrier I has descended 70 with the plate into the fixing solution carried by compartment I², in which it is held suspended until the fourth pin of disk R has moved into engagement with the fourth finger of star-wheel P^{10} . The movement represented 75 by 4 5 now takes place. Bath K is released, shifted backward a step to bring the water compartment under the carrier by the oscillation of latch T by a second pin on cam P^5 , as already described. At the completion of this 80 movement the carrier I and the plate held therein descends into the washing-water in compartment K³, as is evident from the construction of cam P' , and is there held until the fifth pin of disk R has moved into engagement with the fifth finger of the star-wheel 85 P^{10} . At the completion of the fourth fifth of the movement cam P^3 also becomes operative, as it is provided with a notch on the radial line s . It operates to shift the plug m^2 of 90 valve M^3 , admitting water to the compartment. 95 It is not essential that there should be a separate cylinder for controlling the cock for the inflow of water. If water is used as the 100 motive fluid for the cylinders, port m^6 of the valve M^3 will be permanently closed and the construction of the plug and the valve may be otherwise the same as the other plugs and valve-blocks. If air is used, the port m^5 may 105 be permanently closed and a water-supply connected with port m^6 , or port m^6 may be closed and water-supply connected with the port m^5 . Of course the various parts connected to the plug m^2 of this valve will be 110 properly related to open and close the valve at the proper time. A flexible tube V carries off the overflow from chamber K³. Further movement of the motor carries the fifth pin of disk R into contact with fifth finger of the 115 star-wheel P^{10} and the cam-shaft has commenced the movement 5 1. Cam P' operates to withdraw the plate from the compartment K³, cam P^3 to shut off the flow of water, and the latch T is withdrawn to permit the backward movement of the bath to its farthest 120 backward position, in which compartment K⁴ of the bath is directly under the plate. The dog I² is now released by the action of cam P^2 , the suspended plate drops into compartment, 125 and the jaws H H come together to receive and support the next plate through the action of cam P^6 , which operates to release the pressure from cylinder h⁵, the piston of the same being thus forced outward in a manner well 130 understood. Further rotation of the cam-shaft P^8 releases the pressure from cylinder K⁶ through the means of cam P^5 and intermediate mechanism. The bath K is carried for

ward by the retractive device to the position shown in Fig. 1, the slide L' is drawn aside, and the finished plate descends through the delivery-chute in a manner already described.

- 5 Before the cam-shaft has completed its movement the pressure has been released from cylinder N and the slide withdrawn from the coin-slot. The parts have now returned to their original position and are ready to again 10 be set in operation by the insertion of a new coin.

Having described my invention, what I consider as new, and desire to secure by Letters Patent, is—

- 15 1. In an automatic photographing apparatus, the combination of a plate-carrier and its operating means, means for controlling the exposure of the plate, a bath for holding the liquid in which the plate is to be immersed, 20 and means for causing a relative movement of the plate-carrier and bath, a suitable motor fluid, and automatic control devices regulating in proper order and time the flow of motor fluid to and from each of said means, 25 substantially as described.

2. In an automatic photographing-machine, the combination of a plate-carrier, a bath for holding the liquids in which the plate is to be immersed, means for controlling the exposure 30 of the plate, means for engaging the plate with and disengaging it from the plate-carrier, a device for causing a relative movement of the plate-carrier and the bath, actuated by a suitable motive fluid, and means for controlling the flow of the motive fluid to said device, substantially as specified.

3. The combination of a plate-carrier, a bath for holding the liquids in which the plate is to be immersed, means for controlling the 40 exposure of the plate, a device for causing a relative movement of the plate-carrier and the bath, actuated by a suitable motive fluid, and means for controlling the flow of the motive fluid to and from said device to produce 45 the proper sequence in the relative movements of the plate-carrier and the bath, substantially as specified.

4. The combination of a plate-magazine, a plate-holder, a plate-carrier, an engine for 50 causing a movement of the magazine to deliver contained plates to the plate-holder, an engine for operating the jaws of the plate-holder, an engine for operating the plate-carrier, and a device for controlling the flow of 55 motive fluid to the several engines, substantially as specified.

5. In an automatic photographing-machine, the combination of a shutter, a movable carrier, a movable bath containing the liquids in 60 which the plate is to be immersed, engines for moving said shutter, plate-carrier and bath, a series of valves for controlling the flow of the motive fluid to the engines, a series of cams for operating the valves, and a 65 motor for operating the cams, substantially as specified.

6. In an automatic photographing-machine, the combination of a movable plate-carrier, a movable bath containing the liquids in which the plate is to be immersed, engines 70 for moving said carrier and said bath actuated by a suitable fluid, means for supplying a current of water to wash the plate while the plate is immersed therein, and a motor for controlling the flow of fluid to the engines, 75 substantially as specified.

7. A movable plate-carrier for an automatic photographing-machine comprising in combination a movable frame, an engine or engines for moving the frame, an engine carried by 80 the frame, a gripping device operated by the second engine to sustain the plate in the frame or release it therefrom and means for controlling the flow of motive fluid to and from the engines to operate the movable frame and 85 gripping device, substantially as specified.

8. In an automatic photographing-machine, the combination of a movable carrier, an engine or engines for operating the same, a movable bath containing the liquids in which 90 the plate is to be immersed, an engine for moving the bath, and a device for controlling the flow of motive fluid to and from said engines to successively immerse the plate in the various liquids and finally deposit it in a compartment of the bath, substantially as specified. 95

9. In an automatic photographing-machine, the combination of a movable carrier, an engine or engines for operating the same, a 100 movable bath containing the liquids in which the plate is to be immersed, an engine for moving the bath and a device for controlling the flow of motive fluid to and from said engines to successively immerse the plate in the 105 various liquids and retain them therein a period of time, substantially as specified.

10. In an automatic photographing-machine, the combination of a plate-carrier, a movable bath, containing the liquids in which 110 the plate is to be immersed, means for controlling the exposure of the plate, engines for moving said plate-carrier and said bath operated by a suitable motive fluid, a series of valves for controlling the flow of the motive 115 fluid to and from the engines, a shaft for controlling the movement of the valves, a motor for moving said shaft and means intermediate between the motor and the shaft for controlling the movement of the latter, substantially 120 as specified.

11. In an automatic photographing-machine, the combination of a plate-carrier, a bath containing the liquids in which the plate is to be immersed, means for controlling the 125 exposure of the plate, a shaft for controlling the movement of the plate-carrier, a motor for moving the shaft and means for controlling the movement of the shaft comprising a star-wheel provided with a plurality of fingers or projections, and a series of pins adapted to coact with said fingers or projections, 130

said star-wheel and pins being arranged intermediate of the motor and the shaft, substantially as specified.

12. In an automatic photographing - machine, the combination of a plate-carrier, a bath for holding the liquids in which the plate is to be immersed, a device for causing a relative movement of the plate-carrier and the bath, actuated by a suitable motive fluid, a rotary shaft for controlling the movement of the motive fluid to said device, a motor for actuating the shaft, and means for imparting an intermittent rotary movement to the shaft from the motor, comprising a star-wheel provided with a number of fingers or projections, and a series of pins adapted to coact with said fingers or projections, substantially as specified.

13. In an automatic photographing - machine, the combination of a rotary shaft, a motor for actuating the shaft and means for imparting an intermittent rotary movement

to the shaft from the motor comprising a star-wheel provided with a number of fingers or projections, and a series of adjustable pins, 25 adapted to coact with said fingers or projections, substantially as specified.

14. In an automatic photographing - machine, the combination of a movable carrier, an engine for moving the same, a bath containing the liquids in which the plate is to be immersed and a device for controlling the flow of motive fluid to and from said engine to successively immerse the plate in and elevate it from the liquids in said bath, substantially as 35 specified.

In testimony whereof I have signed my name to this specification in the presence of two subscribing witnesses.

JOSEPH F. RADERS.
